U.S. Cl. D55—1 C

FIG. 1

FIG. 2

FIG. 3

FIG. 4

FIG. 5

FIG. 1 is an isometric view of a chain link for poultry feed conveyor embodying my design.

FIG. 2 is a top view of the chain link for poultry feed conveyor shown in FIG. 1.

FIG. 3 is a side view of the chain link for poultry feed conveyor shown in FIG. 1 and FIG. 2, the hidden side having the same appearance as that visible.

FIG. 4 is a section taken at 4—4 in FIG. 3.

FIG. 5 is a view similar to FIG. 4 of a modified form of the chain link shown in FIGS. 1—4, in which the only difference therefrom is shown.

FIG. 6 is a side view of a further embodiment of the chain link disclosed and described herein shown in partial section.

FIG. 7 is a section taken at 7—7 in FIG. 6; and FIG. 8 is a section taken at 8—8 in FIG. 6.

FIG. 6 is conversely a section viewed substantially at 6—6 in FIG. 7.

It is to be further understood that the top and side views of the chain link embodiment shown in FIGS. 6, 7, and 8, have the appearance shown in FIGS. 2 and 3.

This application is a continuation-in-part of my copending application Ser. No. 314,856, filed Dec. 13, 1972, and entitled Poultry Feeder Chain.

I claim:

The ornamental design for a chain link for poultry feed conveyor, as shown and described.
